UNITED STATES PATENT OFFICE

92,776

DESIGN FOR AN AQUARIUM

Oscar M. Shannon, Larchmont, N. Y.

Application October 16, 1933, Serial No. 49,498

Term of patent 3½ years

To all whom it may concern:

Be it known that I, OSCAR M. SHANNON, a citizen of the United States, residing in Larchmont, county of Westchester, State of New York, have invented a new, original, and ornamental Design for an Aquarium, of which the following is a specification, reference being had to the accompanying drawing, forming a part thereof.

The figure is a perspective view of an aquarium embodying the design.

A dominant feature of the design is a wooden

or metallic frame substantially as shown, with a glass aquarium therein or with a metal frame aquarium therein having transparent windows registering with the windows of the wooden or metallic frame.

I claim:

The ornamental design for an aquarium, substantially as shown and described.

In witness whereof, I have hereunto affixed my hand, this 9th day of October, 1933.

OSCAR M. SHANNON.
